UNITED STATES PATENT OFFICE.

WILLIAM FULLER HOSFORD, OF MAPLEWOOD, NEW JERSEY, ASSIGNOR TO WESTERN ELECTRIC COMPANY, INCORPORATED, OF NEW YORK, N. Y., A CORPORATION OF NEW YORK.

METHOD AND APPARATUS FOR COATING CORES.

Application filed February 26, 1923, Serial No. 621,241. Renewed October 20, 1926.

This invention relates to a method and apparatus for coating cores.

The object of the invention is to produce a core having a coating of pulp thereon which is attached to the core solely by an intermingling of the fibers thereof and without the use of any adhesive substance.

Briefly, the method consists in depositing 10 pulpos material upon a foraminous member, transferring the material from said member to a carrier, preferably a felt, removing the pulpos material from the carrier and depositing it on the core, and then forming the said material around the core 15 so that it constitutes a homogeneous coating thereon.

The present method may be employed to 20 advantage for insulating electrical conductors, but it is to be understood that it is not limited to this purpose but only in so far as is defined by the appended claims. Where the method is used for insulating electrical conductors manila, wood, rag, cotton, esparto, jute, hemp, and asbestos pulps may 25 be employed as the coating material, but other materials than those specified may be used without departing from the spirit and scope of the present invention which contemplates in its broadest aspect the coating 30 of any core with pulp.

The drawings illustrate an apparatus by 35 which the method may be practiced, the apparatus being especially designed for coating a core in strand form, but it is to be understood that other apparatus may be devised for coating cores in other forms without departing from the spirit and scope of the invention.

The word "pulp" as used in the specification 40 and claims is to be understood as defining and including any cohering fibrous mass whether suspended in a liquid, moist, or substantially dry.

In the accompanying drawings,

Fig. 1 is a side elevation of a preferred 45 apparatus by which the method may be practiced;

Fig. 2 is an enlarged top plan view of the 50 apparatus shown in Fig. 1, parts being omitted for the sake of clearness;

Fig. 3 is an enlarged fragmentary top

plan view of part of the apparatus shown in Fig. 1;

Fig. 4 is an enlarged fragmentary top plan view of part of the apparatus shown 55 in Fig. 3;

Fig. 5 is an enlarged view showing the form of the pulp coating after it has been deposited on the core by the carriers, and

Figs. 6, 7 and 8 are enlarged views showing 60 the form of the pulp coating as it is delivered from the squeeze rolls, during the forming operation, and after the forming operation is completed respectively.

The steps of the method will be readily 65 understood from a detailed description of the apparatus by which the method may be practiced.

Referring to the drawings in detail in 70 which like reference numerals designate similar parts throughout the several views, 10 represents a framework which supports all of the elements of the apparatus. Mounted on the framework 10 are two tanks 11 and 12 each containing a mixture of pulp 75 and liquid, the liquid being preferably water. The tank 12 is mounted at a lower level than the tank 11, the purpose of which will hereinafter appear. Rotatably mounted within the tanks 11 and 12 are drums 13 80 and 14 respectively. Each of these drums comprises imperforate side walls and a peripheral portion 15 provided with a plurality of large perforations 16 (Fig. 4) covered with a fine wire mesh 17. The 85 drums are each provided with a centrally disposed axle 18 which is rotatably mounted in suitable bearings 19 carried by the framework 10.

The drums 13 and 14 are rotated in the 90 directions indicated by the arrows by means of belts or other suitable means connected with a source of power (not shown). As these drums are rotated in their respective tanks, pulpos material is deposited on the 95 wire mesh 17 carried thereby. The deposit is obtained by maintaining the pulp mixture within the drums at a lower level than that of the level of the pulp mixture in the tanks, as indicated by dotted lines A and B respectively. This difference in levels is maintained by siphon pipes 20 and 21 which 100

have their inlet openings submerged in the pulp mixture within the drums 11 and 12 and their discharge through the tubular axles 18. A continuous circulation of the pulp mixture is maintained in the tanks 11 and 12 by feeding the pulp mixture from suitable supply tanks (not shown) into the tanks 11 and 12 through pipes 22 and 23 respectively, and out of the said tanks through pipes 24 and 25 respectively into suitable receiving tanks (not shown) from which the pulp mixture is pumped back into the supply tanks in any suitable manner. Due to the difference in levels of the liquid within the drums and tanks, the liquid in the tanks will pass through the fine wire mesh 17 secured to each drum and perforations 16 made in the said drums into the interior of the drums, straining pulp onto the outer surface of the wire mesh 17.

Associated with the drum 13 is an endless belt 26 made preferably of felt. The belt is rotatably supported on rollers 27 and 28 rotatably mounted in suitable bearings carried by pairs of standards 29 and 30 respectively which are supported by the framework 10. The felt 26 is disposed directly above the drum 13 and is of a width slightly greater than the width of the fine wire mesh 17 carried by the drum, as shown in Fig. 4. The felt 26 is pressed against the fine wire mesh 17 carried by the drum 13 by means of a roll 31. This roll is forced toward the drum, squeezing the felt between it and the fine wire mesh 17, carried by the drum, by suitable pressure means 32 which is adjustable to present the proper pressure upon the felt. The roll 31 and its pressure means 32 are carried by a pair of standards 33 supported by the framework 10.

Associated with the drum 14 is a belt 34, preferably made of felt and similar to the belt 26. The belt 34 is rotatably supported upon the rollers 35 and 36 rotatably mounted within pairs of standards 37 and 38 respectively supported by the framework 10. The belt 34 is disposed directly above the fine wire mesh 17 carried by the drum 14 and is of a width slightly greater than the wire mesh as shown in Fig. 4. The belt 34 is pressed against the fine wire mesh 17, carried by the drum 14, by means of a roller 39 which is forced toward the drum by suitable pressure means 40 which may be adjustable to present the requisite pressure to squeeze the belt between the roller 39 and the fine wire mesh 17 carried by the drum 14. The roller 39 and its pressure means 40 are carried by a pair of braces 41 attached to the standards 37 and 38.

The two belts 26 and 34 are rotated in the directions indicated by arrows by means of belts or any other suitable means which are connected with a suitable source of power (not shown). As the belts are rotating they

are pressed against the fine wire mesh 17 on the drums 13 and 14, as previously described, and since the fine wire mesh carries pulpoous material, deposited thereon by the rotation of the drums 13 and 14 within their respective tanks, this pulpoous material will be transferred to the belts 26 and 34 in a manner well understood by those skilled in the art. In addition to transferring the pulpoous material to the belts, most of the "free liquid" in the pulp mixture will be squeezed out, partly through the felts and partly through the fine wire mesh 17 on each of the drums 13 and 14. The pulpoous material on the felts 26 and 34, which clings thereto in the form of a narrow ribbon, is carried by the felts toward the right as viewed in Fig. 1.

The core to be coated is fed from a supply reel 42 between the felts 26 and 34, the core lying between the pulpoous ribbons carried by the felts 26 and 34 respectively, as shown at C in Fig. 4. The roller 28 is forced against the roller 36 by suitable pressure means 43 which serves to squeeze the felts 26 and 34 against diametrically opposite sides of the core as the felts and core pass between the said rolls. These rolls serve to force the pulpoous ribbons carried by the felts 26 and 34 together so that they felt with each other to some extent, whereby the core upon its exit from between the rolls 28 and 36 carries the pulpoous ribbons in the form shown in Fig. 5.

The core carrying the ribbons of pulpoous material are then passed between the squeezing rolls 44 and 45 which are rotatably mounted between a pair of brackets 46 secured to a pair of upright standards 47 carried by the framework 10. The rolls 44 and 45 are rotated by means of a belt or other suitable means connected with a source of power (not shown) and serve preferably to draw the core to be coated from the supply 42 between the belts 26 and 34 and then between the rolls themselves. The rolls 44 and 45 may be made of any suitable material, the roll 45 being preferably made of rubber and the roll 44 in the form of a drum covered with a belt 48, as shown in Fig. 2. The rolls 44 and 45 remove the greater portion of the liquid from the pulp ribbons and form them into a single thin ribbon which extends laterally from each side of the core, as shown in Fig. 6. This squeezing operation also tends to mat or felt the fibers of the pulp into more intimate relation, increase the tensile strength of the covering and secure it to the core.

From the squeezing rolls the core with its ribbon pulp coating is drawn through a former 50 which wraps the projecting edges of the ribbon around the core and around each other, the appearance of the coating after it is first acted upon by the former

and after the forming action is completed being clearly shown in Figs. 7 and 8. The former causes a thorough intermingling of the pulp fibers and shapes the coating so that it embraces the core and conforms to the shape thereof and molds the coating into a mass so homogeneous that upon cutting the core and the coating, the latter will not fray or ravel and will not become easily detached from the core.

The former 50 comprises essentially two plates which are rotated around the core and serve to wrap the pulp ribbon around the core in much manner as though the core and pulp ribbon were rolled on a table top with the palm of the hand. The former 50 shown in the drawings, is identical with that fully described in the co-pending application of Walker and March, Serial No. 20 547,923, filed March 29, 1922, and for a detailed description of this mechanism reference is made to the application above referred to.

The core with its formed coating is drawn from the former and subjected to a mechanism for thoroughly drying out the coating. The means shown for performing this operation are a pair of wide hollow drums 52 and 53 heated internally and having a plurality of grooves 54 formed thereon, Fig. 2, which receive the core, guides (not shown) being provided for directing the core over first one drum and then the other until it has traversed all of the grooves on both drums, after which it is stored on a receiving drum 55. The drums 52 and 53 are revolvably mounted in suitable bearings carried by vertical standards supported by the framework. The drums 52 and 53 and the take-up reel 55 are rotated by belts or other suitable means connected with a source of power (not shown).

Although it has been stated that the primary object of the invention is to apply a coating of pulp to a core without the use of any adhesive substance, the machine herein disclosed may be used with a pulp mixture containing a sizing substance, or the pulp may be deposited on a core which has been previously treated with an adhesive agent, without departing from the spirit and scope of the present invention.

Although the machine herein disclosed is designed for coating one core at a time, it is to be understood that the mechanism may be modified to handle a plurality of cores simultaneously.

What is claimed is:

1. The method of coating a core in strand form with pulp, which consists in depositing wet pulpy material on a foraminous member, simultaneously removing said material from said member and removing some of the moisture therefrom, depositing said material on the core, and forming said ma-

terial around the core in such manner that the material is attached to the core solely by an intermingling of the fibres thereof.

2. The method of coating a core in strand form with pulp, which consists in depositing wet, pulpy material on a foraminous member, simultaneously removing said material from said member and removing some of the moisture therefrom, depositing said material on the core, forming said material around the core, and then removing substantially all of the moisture from said material.

3. The method of coating a core in strand form with pulp, which consists in depositing wet pulpy material on a foraminous member, simultaneously removing said material from said member and removing some of the moisture therefrom, depositing said material on the core, forming said material around the core in such manner that said material is attached to the core solely by an intermingling of the fibres thereof, and then removing substantially all of the moisture from said material.

4. The method of coating a core in strand form with pulp, which consists in depositing a ribbon of moist pulpy material on a member, removing said ribbon from said member, causing contact between said ribbon and the core, and then wrapping the said ribbon around the core.

5. The method of coating a core in strand form with pulp, which consists in depositing a ribbon of moist pulpy material on a member, removing said ribbon from said member, causing contact between said ribbon and the core, and then wrapping said ribbon around the core in such manner that it is attached to the core solely by an intermingling of the fibers thereof.

6. The method of coating a core in strand form with pulp, which consists in depositing a ribbon of wet, pulpy material on a foraminous member, removing said ribbon from said member, removing a portion of the moisture from said ribbon, causing contact between the ribbon and the core, and then wrapping said ribbon around the core.

7. The method of coating a core in strand form with pulp, which consists in depositing a ribbon of wet pulpy material on a foraminous member, removing said ribbon from said member, removing a portion of the moisture from said ribbon, causing contact between the ribbon and the core, and then wrapping said ribbon around the core in such manner that it is attached to the core solely by an intermingling of the fibres thereof.

8. The method of coating a core in strand form with pulp, which consists in depositing a ribbon of wet, pulpy material on a foraminous member, removing said ribbon from said member, removing a portion of the moisture from said ribbon and deposit-

ing the ribbon on the core longitudinally of the core, and then wrapping said ribbon around the core.

9. The method of coating a core in strand 5 form with pulp, which consists in depositing a ribbon of wet pulpy material on a foraminous member, removing said ribbon from said member, removing a portion of the moisture from said ribbon, depositing 10 a ribbon on the core longitudinally of the core, and then wrapping said ribbon around the core in such manner that it is attached to the core solely by an intermingling of the fibres thereof.

13. 10. The method of coating a core in strand form with pulp, which consists in depositing a ribbon of wet, pulpy material on a foraminous member, removing said ribbon from said member, removing a portion of 20 the moisture from said ribbon, causing contact between the ribbon and the core, wrapping said ribbon around the core, and then removing substantially all of the moisture from said wrapping.

25. 11. The method of coating a core in strand form with pulp, which consists in depositing a ribbon of wet pulpy material on a foraminous member, removing said ribbon from said member, removing a portion of 30 the moisture from said ribbon, causing contact between the ribbon and the core, wrapping said ribbon around the core in such manner that it is attached to the core solely by an intermingling of the fibres thereof, 35 and then removing substantially all of the moisture from said wrapping.

12. The method of coating a core in strand form with pulp, which consists in depositing pulpy material on a member, transferring 40 said material from said member to a carrier, then removing said material from the carrier and depositing it on the core, and then wrapping the material around the core.

45. 13. The method of coating a core in strand form with pulp, which consists in depositing pulpy material on a member, transferring said material from said member to a carrier, then removing said material from the carrier and depositing it on the core, 50 and then wrapping the material around the core in such manner that it is attached to the core solely by an intermingling of the fibres thereof.

55. 14. The method of coating a core in strand form with pulp, which consists in depositing pulpy material on a member, transferring said material from said member to a felt, then removing said material from the felt and depositing it on the core, and then 60 wrapping the material around the core.

15. 15. The method of coating a core in strand form with pulp, which consists in depositing pulpy material on a member, transferring said material from said member to a felt, and removing said material from the

felt and depositing it on the core, and then forming said material around the core.

16. The method of coating a core in strand 70 form with pulp, which consists in depositing a ribbon of wet pulpy material on a member, transferring said ribbon from said member to a felt, removing said ribbon from the felt and depositing it on the core, and then forming said ribbon around the core.

17. The method of coating a core in strand 75 form with pulp, which consists in depositing a ribbon of wet pulpy material on a foraminous member, transferring said ribbon from said member to a felt, removing said ribbon from the felt and depositing it on the core, and then forming said ribbon around the core. 80

18. The method of coating a core in strand 85 form with pulp, which consists in depositing wet, pulpy material on a foraminous member, transferring said material from said member to a felt, removing some of the moisture from said material, removing said material from the felt and depositing it on the core, forming said material around the core, and then removing substantially all of the moisture from said material. 90

19. The method of coating a core, in strand 95 form with pulp, which consists in depositing a ribbon of wet, pulpy material on a foraminous member, simultaneously transferring said ribbon from said member to a felt and partially removing the moisture 100 from said ribbon, removing said ribbon from the felt and depositing it on the core, and then forming said ribbon around the core.

20. The method of coating a core in strand 105 form with pulp, which consists in depositing a ribbon of wet, pulpy material on a foraminous member, simultaneously transferring said ribbon from said member to a felt and partially removing the moisture 110 from said ribbon, removing said ribbon from the felt and depositing it on the core, forming said ribbon around the core, and then removing substantially all of the moisture from 115 said wrapping.

21. The method of coating a core in strand form with pulp, which consists in depositing a ribbon of pulpy material on a member, transferring said ribbon from said member to a moving felt, and then removing said 120 ribbon from the felt and depositing it on the core, and then wrapping said ribbon around the core in such manner that it is attached to the core solely by an intermingling of the fibres thereof. 125

22. The method of coating a moving core in strand form with pulp, which consists in depositing a ribbon of wet, pulpy material on a foraminous member, simultaneously transferring said ribbon from said member 130

to a moving felt and removing some of the moisture from said ribbon, removing said ribbon from the felt and depositing it on the moving core, and then wrapping said ribbon around the core.

23. The method of coating a moving core in strand form with pulp, which consists in depositing a ribbon of wet pulpous material on a foraminous member, simultaneously

10 transferring said ribbon from said member to a moving felt and removing some of the moisture from said ribbon, removing said ribbon from the felt and depositing it on the moving core, and then wrapping said ribbon around the core in such manner that it is attached to the core solely by an intermingling of the fibres thereof.

24. The method of coating a moving core in strand form with pulp, which consists in

20 depositing a ribbon of wet, pulpous material on a foraminous member, simultaneously transferring said ribbon from said member to a moving felt and removing some of the moisture from said ribbon, 25 then removing said ribbon from the felt and depositing it on the moving core, then wrapping said ribbon around the core to constitute a homogeneous coating therefor, and then removing substantially all of the 30 moisture from said coating.

25. The method of coating a moving core in strand form with pulp, which consists in depositing wet, pulpous material on a foraminous member, simultaneously removing

35 said material from said member removing some of the moisture therefrom, depositing said material on the moving core, removing additional moisture from said material, forming said material around the moving 40 core to constitute a homogeneous coating therefor, and then removing substantially all of the moisture from said coating.

26. In a machine for coating a core in strand form with pulp, a supply of liquid

45 containing pulp, a foraminous member, means for causing relative movement between said member and said liquid whereby pulp is strained onto said member, means for removing said pulp from the foraminous 50 member and depositing it on the core, and a former for shaping the pulp so that it conforms with the shape of the core.

27. The method of coating a core in strand form with pulp, which consists in forming 55 two strips of wet pulpous material, depositing said strips upon the core at opposite sides thereof, and then forming said strips so that they constitute a homogeneous covering for the core.

60 28. The method of coating a core in strand form with pulp, which consists in forming two strips of wet pulpous material, depositing said strips upon the core at opposite sides thereof, and then forming said strips 65 around the core in such manner that they

are attached to the core solely by an intermingling of the fibres thereof.

29. The method of coating a core in strand form with pulp, which consists in forming a plurality of strips of wet, pulpous material, 70 depositing said strips upon the core, and then forming said strips so that they constitute a homogeneous covering for the core.

30. The method of coating a core in strand 75 form with pulp, which consists in forming a plurality of strips of wet pulpous material, depositing said strips upon the core, and then forming said strips around the core in such manner that they are attached to the 80 core solely by an intermingling of the fibres thereof.

31. The method of coating a core in strand form with pulp, which consists in forming a plurality of strips of wet, pulpous 85 material, depositing said strips upon the core, then forming said strips so that they constitute a homogeneous covering for the core, and then removing substantially all of the moisture from said coating. 90

32. The method of coating a core in strand form with pulp, which consists in forming a plurality of strips of wet, pulpous material, depositing said strips upon the core, removing some of the moisture from said 95 strips and then forming said strips so that they constitute a homogeneous covering for the core.

33. The method of coating a core in strand form with pulp, which consists in forming a 100 plurality of wet strips of pulpous material, depositing said strips upon the core and then wrapping said strips around the core so that they constitute a homogeneous covering for the core. 105

34. The method of coating a core in strand form with pulp, which consists in forming two strips of wet, pulpous material, depositing said strips upon the core and at opposite sides thereof, and then wrapping 110 said strips around the core so that they constitute a homogeneous coating for the core.

35. The method of coating a core in strand form with pulp, which consists in forming two strips of wet, pulpous material, depositing said strips upon the core and at opposite sides thereof, wrapping said strips around the core so as to constitute a homogeneous covering therefor, and then removing substantially all of the moisture from said covering. 115

36. The method of coating a core in strand form with pulp, which consists in forming two strips of wet, pulpous material, depositing said strips upon the core and at opposite sides thereof, removing some of the moisture from said strips, and then wrapping said strips around the core so that they constitute a homogeneous coating for the core. 120

37. The method of coating a core in strand 125

- form with pulp, which consists in forming two strips of wet, pulpoous material, depositing said strips upon the core and at opposite sides thereof, removing some of the moisture 5 from said strips, and then wrapping said strips around the core so that they constitute a homogeneous coating for the core, and then removing substantially all of the moisture from said coating.
- 10 38. In a machine for coating a core in strand form with pulp, a plurality of foraminous members, means for depositing pulpoous material upon said members, a carrier associated with each foraminous member and 15 in contact therewith, means for causing relative movement between the carriers and said foraminous members whereby the pulp thereon is transferred to the carriers, means for bringing the core to be coated into contact with the pulp on both of said carriers, and means for causing relative movement between the said carriers and the core whereby the pulp on the carriers is deposited upon the core.
- 20 39. In a machine for coating a core in strand form with pulp, a plurality of foraminous members, means for depositing pulpoous material upon said members, a carrier associated with each foraminous member and 25 in contact therewith, means for causing relative movement between the carriers and said foraminous members whereby the pulp thereon is transferred to the carriers, said carriers arranged adjacent each other, means for inserting the core to be coated between said carriers and in contact with the pulp on the carriers, and means for causing relative movement between said carriers and the core whereby the pulp on the carriers is deposited 30 on the core.
- 40 40. In a machine for coating a core in strand form with pulp, a plurality of foraminous members, means for depositing pulpoous material upon said members, a carrier associated with each foraminous member and 45 in contact therewith, means for causing relative movement between the carriers and said foraminous members whereby the pulp thereon is transferred to the carriers, said carriers arranged adjacent each other, means for inserting the core to be coated between said carriers and in contact with the pulp on the carriers, and means for causing relative movement between said carriers and the core whereby the pulp on the carriers is deposited 50 on the core.
- 55 41. In a machine for coating a core in strand form with pulp, a plurality of foraminous members, means for depositing pulpoous material upon said members, a carrier associated with each foraminous member and 60 in contact therewith, means for causing relative movement between the carriers and said foraminous members whereby the pulp thereon is transferred to the carriers, said carriers arranged adjacent each other, means for inserting the core to be coated between said carriers, means for pressing said carriers toward the core and against each other, and means for causing relative movement 65 between said carriers and the core whereby the pulp on the carriers is deposited on the core.
- 70 42. In a machine for coating a core in strand form with pulp, a plurality of foraminous members, means for depositing pulpoous material upon said members, a carrier associated with each foraminous member and 75 in contact therewith, means for causing relative movement between the carrier and said foraminous members whereby the pulp thereon is transferred to the carriers, said carriers arranged adjacent each other, means for inserting the core to be coated between said carriers, means for pressing said carriers toward the core and against each other, said carriers engaging the core at opposite sides 80 thereof, and means for causing relative movement between the carriers and the core whereby the pulp on the carriers is deposited on the core.
- 85 43. In a machine for coating a core in strand form with pulp, a plurality of foraminous members, means for depositing wet, pulpoous material upon said members, a carrier associated with each foraminous member and 90 pressed into contact therewith, means for causing relative movement between the carriers and said foraminous members whereby the pulp thereon is transferred to the carriers and some of the moisture is removed from said material, means for bringing the core to be coated into contact with the pulp on both of said carriers and means for causing relative movement between said carriers and the core whereby the pulp on the carriers is deposited upon 95 the core.
- 100 44. In a machine for coating a core in strand form with pulp, a plurality of foraminous members, means for depositing wet, pulpoous material upon said members, a carrier associated with each foraminous member and 105 pressed into contact therewith, means for causing relative movement between the carriers and said foraminous members whereby the pulp thereon is transferred to the carriers and some of the moisture is removed from said material, means for bringing the core to be coated into contact with the pulp on both of said carriers, and means for causing relative movement 110 between said carriers and the core whereby the pulp on the carriers is deposited upon the core, and means for forming said material on the core so that its constitutes a homogeneous coating therefor.
- 115 120 125 130

45. In a machine for coating a core in strand form with pulp, a plurality of foraminous members, means for depositing wet, pulpous material upon said members, a carrier associated with each foraminous member and pressed in contact therewith, means for causing relative movement between the carriers and said foraminous members whereby the pulp thereon is transferred to the carriers and some of the moisture is removed from said material, means for bringing the core to be coated into contact with the pulp on both of said carriers, and means for causing relative movement between said carriers and the core whereby the pulp on the carriers is deposited upon the core, and means for forming said material on the core so that it constitutes a homogeneous coating therefor, and means for removing substantially all of the moisture from said coating. 85
46. In a machine for coating a core in strand form with pulp, a plurality of foraminous members, means for depositing pulpous material on said members, a plurality of felts associated with said members and in contact therewith, means for causing relative movement between said felts and said foraminous members whereby the pulp on said members is transferred to said felts, means for bringing the core to be coated into contact with the pulp on said felts, and means for causing relative movement between said felts and the core whereby the pulp material on the felts is deposited on the core. 95
47. In a machine for coating a core in strand form with pulp, a plurality of foraminous members, means for depositing pulpous material on said members, a plurality of felts associated with said members and in contact therewith, means for causing relative movement between said felts and said foraminous members whereby the pulp on said members is transferred to said felts, said felts disposed in contact with each other, means for inserting the core to be coated between the contacting portions of said felts, and means for causing relative movement between said felts and the core whereby the pulp material on the felts is deposited on the core. 105
48. In a machine for coating a core in strand form with pulp, a pair of rotatable foraminous members, means for depositing wet, pulpous material on said members, a rotatable felt associated with each of said members and pressed into contact therewith, means for rotating said foraminous members and said felts whereby the pulpous material on the members is transferred to the felts, said felts disposed in contact with each other, and means for drawing the core to be coated between the contacting portions of said felts whereby the pulpous material thereon is deposited on the core. 125
49. In a machine for coating a core in strand form with pulp, a pair of rotatable foraminous members, means for depositing wet, pulpous material on said members, a rotatable felt associated with each of said members and pressed into contact therewith, means for rotating said foraminous members and said felts whereby the pulpous material on the members is transferred to the felts, and some of the moisture is removed from said material, said felts disposed in contact with each other, and means for drawing the core to be coated between the contacting portions of said felts, whereby the pulpous material thereon is deposited on the core, and means for forming the material on the core so that it constitutes a homogeneous coating for the core, and means for removing substantially all of the moisture from said coating. 130
50. In a machine for coating a core in strand form with pulp, a pair of foraminous members, means for depositing a ribbon of pulpous material on each of said foraminous members, a carrier associated with each of said members and pressed into contact therewith, means for causing relative movement between the carriers and said foraminous members, whereby the pulpous ribbons on said members are transferred to said carriers, said carriers disposed in contact with each other, so that the ribbons carried thereby are laid one upon the other, means for inserting the core to be coated between the said contacting ribbons on the carriers, and means for causing relative movement between the core and said carriers whereby the ribbons on the carriers are deposited on the core. 140
51. In a machine for coating a core with pulp, a pair of foraminous members, means for depositing a ribbon of pulpous material on each of said foraminous members, a carrier associated with each of said members and pressed into contact therewith, means for causing relative movement between the carriers and said foraminous members, whereby the pulpous ribbons on said members are transferred to said carriers, said carriers disposed in contact with each other so that the ribbons carried thereby are laid one upon the other, means for inserting the core to be coated between the said contacting ribbons on the carriers, and means for causing relative movement between the core and said carriers whereby the ribbons on the carriers are deposited on the core. 150
52. In a machine for coating a core with pulp, a pair of foraminous members, means for depositing a ribbon of wet, pulpous material on each of said foraminous members, a carrier associated with each of said

members and pressed into contact therewith, means for causing relative movement between the carriers and said foraminous members, whereby the pulpoous ribbons on 5 said members are transferred to said carriers, and some of the moisture is removed from said ribbons, said carriers disposed in contact with each other, so that the ribbons carried thereby are laid one upon the other, 10 means for inserting the core to be coated between the said contacting ribbons on the carriers, and means for causing relative movement between the core and said carriers whereby the ribbons on the carriers are de- 15 posited on the core, means for wrapping said ribbons around the core so as to constitute a homogeneous coating therefor, and means for removing substantially all of the moisture from said coating.

20 53. The method of coating a core in strand form, which consists in depositing unfinished paper on a foraminous member, removing said unfinished paper from said member, depositing said unfinished paper 25 on the core, and then completing the fabrication of the paper by a wrapping operation.

54. The method of coating a core in strand form, which consists in depositing unfinished paper on a foraminous member, 30 removing said unfinished paper from said member, and then wrapping said unfinished paper around the core in such manner that it is attached to the core solely by an intermingling of the fibres thereof.

55. The method of coating a core in 35 strand form, which consists in depositing unfinished paper on a foraminous member, removing said unfinished paper from said member, depositing said unfinished paper on the core, then completing the fabrication 40 of said unfinished paper and forming it around the core in such manner that it is attached to the core solely by an intermingling of the fibres thereof; and subsequently 45 drying the paper.

56. The method of coating a core in strand form, which consists in forming a plurality of strips of unfinished paper, de- 50 positing said strips upon the core, and then wrapping said strips around the core.

57. The method of coating a core in strand form, which consists in forming two strips of unfinished paper, depositing said strips upon the core at opposite sides there- 55 of, and then forming said strips around the core in such manner that they are attached to the core solely by an intermingling of the fibres thereof.

58. The method of coating a core in strand form, which consists in forming a 60 plurality of strips of unfinished paper, and then wrapping said strips upon the core in such manner that they constitute a homo- geneous covering for the core.

In witness whereof, I hereunto subscribe 65 my name this 15th day of February, A. D., 1923.

WILLIAM FULLER HOSFORD.
